Primary Examiner — Marie D. Fast Horse(74) *Attorney, Agent, or Firm* — Raymond Wagenknecht; Biotech Beach Law PC(57) **CLAIM**

The ornamental design for a computer docking station as shown and described.

DESCRIPTION

FIG. 1 is a top, front, and left perspective view of a computer docking station showing my new design;

FIG. 2 is a bottom, rear, and right perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof; and,

FIG. 9 is a top, rear, and right perspective view of the computer docking station shown in an exemplary environment of use.

The broken lines in FIG. 9 showing the exemplary laptop and cable structures depict environmental subject matter only and form no part of the claim, while all other broken lines depict portions of the computer docking station that form no part of the claimed design.

1 Claim, 7 Drawing Sheets(56)
